COMBINATION POCKET TOILET ARTICLE

Carl E. Ulrich, Modesto, Calif.

Application April 3, 1950, Serial No. 153,627

1 Claim. (Cl. 132—76.2)

1

This invention is directed to, and it is an object to provide, a novel combination pocket toilet article.

Another object of the invention is to provide a combination pocket toilet article which is compact, neat in appearance, and convenient to use.

A further object of the invention is to provide a combination pocket toilet article including a nail file which is arranged so that the article, which includes a holding clip, may remain secured in the pocket when the nail file is withdrawn for use; or, selectively, the entire unit may be withdrawn from the pocket for use.

An additional object of the invention is to provide a combination pocket toilet article including a nail file wherein the nail file is removably mounted, in connection with the handle of the article, in a novel manner which permits of ease of finger engagement with, and removal of, the nail file.

Still another object of the invention is to provide a combination pocket toilet article which is designed for ease and economy of manufacture.

A further object of the invention is to provide a combination pocket toilet article which is practical and reliable, and yet exceedingly effective for the purpose for which it is designed.

These objects are accomplished by means of such structure and relative arrangement of parts as will fully appear by a perusal of the following specification and claim.

In the drawings:

Fig. 1 is a side elevation of the combination pocket toilet article; the view being partly in section and showing the nail file fully inserted in the comb handle.

Fig. 2 is a back edge elevation of the combination pocket toilet article; the view being partly in section and showing the nail file partially withdrawn.

Fig. 3 is a fragmentary elevation showing the nail file as mounted in connection with and projecting from the handle for use.

Referring now more particularly to the characters of reference on the drawings, the novel, combination pocket toilet article comprises a comb, indicated at 1, which comb includes a back 2 and teeth 3.

At its inner end the comb back 2 merges with a shank 4 which is an integral longitudinal extension of said comb back 2; said shank being circular in cross section and projecting, in tight but removable relation, into a tubular handle 5.

The shank then terminates at its outer end short

2

of the corresponding end of the handle 5 whereby to form a bore or socket 6 of limited depth in the outer end portion of said handle 5.

At its outer end the tubular handle 5 is formed with a protective circumferential bead 7, and a holding clip 8, of spring type, is affixed to the handle 5 exteriorly thereof; the point of attachment being adjacent the protective bead 7, and the clip thence extending lengthwise of the handle whereby to engage the outside of a pocket to the end that the device may be securely but removably held in place in said pocket. The handle 5 and clip 8 may be of metal and suitably ornamented to match a pen and pencil set, or the like.

The nail file, indicated generally at 9, comprises a plug 10 adapted to removably engage in the socket 6 in frictional relation, and a relatively short file 11, of flat type, serrated on opposite faces, is fixed in connection with the plug 10 and projects axially from the inner end thereof. The file 11 is formed with a nail cleaning point 12 on its inner end.

When the nail file 9 is in carrying position, the plug 10 is seated in the socket 6, and the file 11 projects into a longitudinal slot 13 in the shank 4.

The depth of socket 6 is lesser than the length of the plug 10, so that even when fully seated in said socket the plug has certain outward projection therefrom. See Fig. 1. The purpose of this projection is to permit of ready finger engagement with the plug 10 to permit of its removal, together with the file 11, from the handle 5.

The nail file 9 is normally in its engaged position in the pocket 6 of handle 5 of the comb 1 (as shown in Fig. 1), and the comb is effectively held in a person's pocket by the clip 8.

If it is desired to use solely the nail file 9 the plug 10 is grasped by the fingers, and the nail file withdrawn from the remainder of the device; the comb 1, together with the handle 5, remaining in the pocket. Thus, it is not necessary to remove the comb from the pocket before the nail file 9 can be used; the plug 10 then serving as its handle. However, if desired, the comb may be removed from the pocket and plug 10 inserted in socket 6 with the file 11 projecting outward, as in Fig. 3, to provide a larger handle for manipulation of said file.

To use the comb, the entire device is removed from the pocket for this purpose, and the nail file 9, being substantially fully enclosed within the handle 5, does not in any way interfere.

The inner end of the tubular handle 5 is

notched, as at 14, with the adjacent end of the comb engaged in the notch to prevent rotation of the handle on shank 4 when the device is in use.

The handle 5 is removable from the shank 4 so that upon comb breakage, a new comb can be substituted and the device continued in use.

The design of the device is such that it is adapted to ready and inexpensive manufacture, and further the device is quite practical and convenient to use.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

In a combination pocket toilet article, a shank at one end thereof, a tubular handle surrounding the shank, said shank terminating at its outer

5 end short of the corresponding end of the handle so as to form a socket opening to the outer end of the handle, a plug adapted to engage in the socket, and a nail file fixed to the plug and projecting from the inner end thereof; there being a longitudinal slot in the shank into which the nail file extends when the plug is engaged in the socket; the shank being circular in cross section and the tubular handle having a notch in its inner end and the adjacent end of the shank having a lateral projection normally seating in the notch.
